UNITED STATES PATENT OFFICE.

EUGENE COOK, OF KALAMAZOO, MICHIGAN.

VEHICLE-SPRING.

SPECIFICATION forming part of Letters Patent No. 414,876, dated November 12, 1889.

Application filed March 7, 1889. Serial No. 302,251. (No model.)

To all whom it may concern:

Be it known that I, EUGENE COOK, a citizen of the United States, residing at Kalamazoo, county of Kalamazoo, State of Michigan, have 5 invented a new and useful Vehicle-Spring, of which the following is a specification.

This invention relates to that class of four-wheeled vehicles in which spiral springs are employed to elastically support the body.

10 The object of the invention is to construct a spring comprising a horizontal spiral and a peculiarly-formed connected elastic loop designed to effect a more desirable spring action in relation to the varying weights of the burden being borne by the spring, and to modify or cushion the reaction of the spiral by means of said loop.

15 In the drawings forming a part of this specification, Figure 1 is an inverted plan of one end, showing two springs attached to the under side of the body, the other end of the body (not here shown) being of course a duplicate of Fig. 1; Fig. 2, a side elevation showing a change in the location of the spring; 20 Fig. 3, a side elevation of the spring, looking from a point below Fig. 4; and Fig. 4 is a plan of the spring in Fig. 3. The two latter figures are enlarged.

25 Referring to the lettered parts of the drawings, the horizontally-spiral part of the spring is shown at B. The bar of which the spring is composed may be square, angular, round, or any suitable form in cross-section. The bar at one end of the spiral B is extended, as 30 at S, forming a portion for attaching to the body D at e. The end S may be attached to the body at another point, as at v, Figs. 1 and 3, if desired. The bar at the other end of the spiral B is carried back in a direction opposite to that of the end S, and is bent around, 35 forming a loop C, and thence extends beneath the end S, as s, and beyond the same to the side bar r in Fig. 1, or to the bolster z or axle, as in Fig. 2, or to any suitable support disconnected from the body D. The end part of 40 a is hinged or pivoted to its support, but needs no swinging shackle or link connection at this point.

In Fig. 3 it will be seen that part of the loop rests against the under side of the body, 50 and that the side of the loop which is extended into the bar a gradually drops away from the body from the point of contact with the body at the left hand in said Fig. 3 when in its normal position, and also when the burden in 55 the vehicle is comparatively light.

The elastic action of the spring is in the spiral, the loop, and a part of the extended portion a. The action on the spiral of course expands and contracts the same, while the action on the loop is to twist the metal forming the same, and the action on the part a springs it vertically. The spring action is so distributed over or into these respective parts that there is less direct action of the spiral or 60 strain upon the same, and the ordinary shock of the reaction of the spiral is lessened or cushioned because of this distribution and the correlation of the described spring action of the different parts of the spring. 70

The advantage of having the parts S a one over the other is that the spring is balanced and less liable to cant over when under strain.

Having thus described my invention, what I claim as new, and desire to secure by Letters 75 Patent of the United States, is—

A vehicle-spring comprising the elastic bar formed into a horizontal spiral, the bar at one end of said spiral being extended back and looped around one side of the spiral, thence 80 forward past the opposite end thereof, forming an end for attachment to a support disconnected from the vehicle-body, the bar at said opposite end of the spiral being extended for attachment to a vehicle-body, substantially as set forth. 85

In testimony of the foregoing I have hereunto subscribed my name in presence of two witnesses.

EUGENE COOK.
